UNITED STATES PATENT OFFICE.

MARTIN A. STRAND, OF NEW RICHMOND, WISCONSIN.

TOE-STRAP AND STIRRUP FOR SKEES.

1,164,886.

Specification of Letters Patent. Patented Dec. 21, 1915.

Application filed March 24, 1913. Serial No. 756,417.

To all whom it may concern:

Be it known that I, MARTIN A. STRAND, a citizen of the United States, residing at New Richmond, in the county of St. Croix 5 and State of Wisconsin, have invented certain new and useful Improvements in Toe-Straps and Stirrups for Skees; and I do hereby declare the following to be a full, clear, and exact description of the invention, 10 such as will enable others skilled in the art to which it appertains to make and use the same.

My invention has for its object to provide an extremely simple and highly efficient 15 stirrup and toe strap for skees, and to such ends, generally stated, the invention consists of the novel construction and arrangement of parts hereinafter described and defined in the claim.

One object had in view in this improved 20 device has been the reduction to a minimum, of the amount of leather necessary. Leather, as is well known, is much more expensive than metal, but the leather is required 25 for contact with the top of the shoe. On the other hand, metal forms a better stirrup for engagement with the edges of the shoe sole. These features are accomplished in my improved device, the preferred form 30 of which is illustrated in the accompanying drawings, wherein like characters indicate like parts throughout the several views.

Referring to the drawings, Figure 1 is a 35 side elevation showing an ordinary skee having my combined stirrup and toe strap applied thereto; Fig. 2 is a view on a much larger scale, showing a portion of the skee and the combined stirrup and toe strap; Fig. 3 is a vertical section taken on the line 40 $x^3 x^3$ on Fig. 2; Fig. 4 is a plan view of the parts shown in Fig. 2; and Fig. 5 is a plan view showing the metallic stirrup forming strap laid out straight.

The skee which is indicated by the number 45 1, is formed with a mortised hole 2 that extends from edge to edge of the central or intermediate portion thereof. The stirrup is formed from a metal strap, preferably of steel or iron, indicated by the number 50 3. This metal strap, at its ends, is formed with toe strap engaging buckles which may be made in different ways. In the drawings, the said strap is shown as formed at one end with a rectangular perforation 4 and with a tongue 5, and at its other

end, it is shown as provided with a rectangular perforation 6 and a tongue 7. The tongue 5 is cut from that portion of the metal strap 3 that is inward of the perforation 4, and it is then turned outward or 60 upward, as best shown in Figs. 3 and 5, so that it overlaps the said perforation 4 and engages the upper end portion of the strap. The tongue 7 is formed by metal left between the two parts of the perforations 6, 65 and it is elongated slightly by pinching the same laterally and upsetting the same, so that it is caused to overlap with that end of the said metal strap. The perforations 4 and 6 and tongues 5 and 7 constitute what 70 may be termed buckles, for engaging and holding the ends of the leather toe strap 8. After the metal strap 3 has been inserted through the mortised hole 2 of the skee, its ends are turned upward, as shown in Figs. 1 75 to 4, inclusive, so as to form the stirrup. The upwardly projecting arms of the stirrup are adapted to engage with the side edges of the shoe sole. This latter feature, however, is not shown in the drawings. The 80 toe strap 8 is formed with eyelets or perforations 9, through which the tongues 5 and 7 are adapted to be passed. The said tongues are quite stiff, but will spring so as to permit adjustments of the toe strap or the 85 application thereof to the stirrup, or the removal thereof, therefrom. They will, however, prevent accidental separation of the toe strap from the stirrup.

With the above described device, it is evident that the leather toe strap is made very short, being only a little more than sufficient to span the space between the upper ends of the stirrup arms. Ordinary buckles are also dispensed with. The only buckles or strap 90 securing devices employed are formed as integral parts of the stirrup. In fact, the combined stirrup and toe strap is made up entirely of two elements, both of which may be easily made and are of small cost. At the 100 same time, the stirrup is strong and durable and in no wise weakens the skee. It cannot possibly work itself loose from the skee, and as the toe strap cannot possibly become accidentally separated from the stirrup, all 105 danger of accidents due to these causes, are eliminated.

What I claim is:

The combination with a skee, of upwardly extended metal straps secured there- 110

to and formed at their upper ends with wide perforations and with relatively narrow integral tongues, said tongues projecting completely across the said perforations and overlapping portions of the said straps adjacent to said perforations, and a flexible toe strap having its ends passed through the said perforations of said metal straps, and

Copies of this patent may be obtained for five cents each, by addressing the "Commissioner of Patents, Washington, D. C."

itself having perforations through which the said tongues are passed.

In testimony whereof I affix my signature in presence of two witnesses.

MARTIN A. STRAND.
